CLAIM

The ornamental design for a wall panel, as shown and described.

DESCRIPTION

FIG. 1 is a top plan view of a wall panel in accordance with one embodiment showing my new design;
 FIG. 2 is a bottom plan view thereof;
 FIG. 3 is a front elevation view thereof, the rear elevational view being a mirror image thereof, the right side view and left side view being identical thereto;
 FIG. 4 is a top plan view of a wall panel showing a second embodiment of my new design;
 FIG. 5 is a bottom plan view of the wall panel shown in FIG. 4;
 FIG. 6 is a front elevational view of the wall panel shown in FIG. 4, the rear elevational view being a mirror image thereof, the right side view and left side view being identical thereto;
 FIG. 7 is a top plan view of a wall panel showing a third embodiment of my new design;
 FIG. 8 is a bottom plan view of the wall panel shown in FIG. 7;

FIG. 9 is a front elevational view of the wall panel shown in FIG. 7, the rear elevational view being a mirror image thereof, the right side view and left side view being identical thereto;
 FIG. 10 is a top plan view of a wall panel showing a fourth embodiment of my new design;

FIG. 11 is a bottom plan view of the wall panel shown in FIG. 10;

FIG. 12 is a front elevational view of the wall panel shown in FIG. 10, the rear elevational view being a mirror image thereof, the right side view and left side view being identical thereto;

FIG. 13 is a top plan view of a wall panel showing a fifth embodiment of my new design;

FIG. 14 is a bottom plan view of the wall panel shown in FIG. 13;

FIG. 15 is a front elevational view of the wall panel shown in FIG. 13, the rear elevational view being a mirror image thereof, the right side view and left side view being identical thereto;

FIG. 16 is a top plan view of a wall panel showing a sixth embodiment of my new design;

FIG. 17 is a bottom plan view of the wall panel shown in FIG. 16;

FIG. 18 is a front elevational view of the wall panel shown in FIG. 16, the rear elevational view being a mirror image thereof, the right side view and left side view being identical thereto;

FIG. 19 is a top plan view of a wall panel showing a seventh embodiment of my new design;

FIG. 20 is a bottom plan view of the wall panel shown in FIG. 19;

FIG. 21 is a front elevational view of the wall panel shown in FIG. 19, the rear elevational view being a mirror image thereof, the right side view and left side view being identical thereto;

FIG. 22 is a top plan view of a wall panel showing an eight embodiment of my new design;

FIG. 23 is a bottom plan view of the wall panel shown in FIG. 22; and,

FIG. 24 is a front elevational view of the wall panel shown in FIG. 22, the rear elevational view being a mirror image thereof, the right side view and left side view being identical thereto.

The use of a separation and a bracket in the drawings is to indicate that the precise length and/or width of the wall panel is not claimed.

The broken lines shown are included for the purposes of illustrating the unclaimed portions of the article and form no part of the claimed design.
